UNITED STATES PATENT OFFICE

2,513,405

TAPE CONDENSER

John T. Drennen, Newburgh, N. Y., assignor to
 American Viscose Corporation, Wilmington,
 Del., a corporation of Delaware

Application October 31, 1945, Serial No. 625,877

2 Claims. (Cl. 19—151)

1

This invention relates to improvements in tape condensers such as are used in dividing a web obtained from a card into a large number of strips which may be converted directly into rovings.

It has heretofore been found that certain fibers, particularly relatively smooth-surfaced fibers, such as some types of artificial fibers; fibers of a tacky nature, such as excessively oiled fibers of wool or any other type (natural or artificial); fibers having a hydrophobic nature which increases their tendency to develop static charges, such as certain synthetic resin fibers, e. g. vinyl chloride-vinyl acetate copolymers, vinylidene chloride polymers, polyethylene, and so on, cannot be satisfactorily handled on tape condensers after being stripped from the doffer cylinder of a card. Whereas no difficulty is encountered in connection with the top dividing roll of a tape condenser, the fibers in the ribbons frequently tend to adhere to the lands of the bottom dividing roll. This causes rupture of the ribbons and the production of irregularities in those that are obtained.

It is the principal object of the present invention to overcome the difficulties mentioned hereinabove and prevent the break-down of the ribbons which proceed about the bottom dividing roll of tape condensers. Other objects and advantages of the invention will be apparent from the drawing and the description thereof hereinafter.

In the drawing which is illustrative of the invention:

Figure 1 is an end elevation with the framework removed showing a portion of the tape condenser to which the invention is applied, and

Figure 2 is a bottom view, partially in cross-section, taken along line II—II of Figure 1.

With reference to the drawing, a carded web 2 is carried on the outer periphery of the doffer or doffing cylinder 3 which rotates in the direction indicated by the arrow, and the web is removed from the doffer by means of the oscillating stripper comb 4. The stripped web 2 then proceeds between the top and bottom dividing rolls 5 and 6, respectively, which form the preliminary portion of a tape condenser. Each of these rolls 5 and 6 comprises a plurality of grooves 7 alternating between lands 8. The grooves in the bottom dividing roll 6 receive tapes 9 while the grooves in the top dividing rolls receive tapes 10 and the grooves of the top dividing roll are offset with respect to the grooves of the bottom dividing roll so that the lands of

2

one roll face the tapes received in the grooves of the other dividing roll. This is the conventional arrangement and permits tapes 9 to tear ribbons 2a from the web 2 by holding said web between the tapes and the lands 8 of the top dividing roll 5 while the tapes 10 proceed in the same manner to form ribbons 2b at the bottom dividing roll 6. The ribbons 2a are carried around the plain guide roll 11 by means of tapes 9, whereas the ribbons 2b are carried about the lower plain guide roll 12 by the tapes 10, ribbons 2a and 2b being fed from this point to the remaining parts of the tape condenser not shown. In order to prevent the ribbons 2b from clinging to the lands 8 instead of to tapes 10 as they proceed around the lower guiding roll 12, a transverse conduit 13 is provided facing this opening between the ribbons and the lands. The conduit 13 is connected to a compressed air supply by conduit 14 and has a plurality of openings 15, which may be fitted with nozzles 16 arranged so that they face the lands 8 of the bottom dividing roll 6. The conduit 13 may be supported on brackets 17, rotatably mounted on a shaft 18, set screws 19 serving to permit angular adjustment and securing of the conduit in an adjusted position upon the shaft 18. As shown, the openings 15 or nozzles 16 are directed so that substantially their entire blast falls upon the lands 8 just in advance of the points of departure of webs 2b carried by the tapes 10. This assures that the ribbons cannot cling to the lands 8 rather than to the tapes 10 and prevent disruption of the ribbons 2b.

The cause of the tendency of the lower surface of web 2 to cling to the lands 8 of the bottom dividing roll, whereas there is no such tendency of the upper surface to cling to the lands 8 of the top dividing roll in spite of the fact that the latter effect would be favored by gravity whereas the former is disfavored is not entirely understood, but appears to be the result of a combination of several factors. First, the exposed surface of the web 2 on the doffer 3 appears to be much more fuzzy and irregular than the surface immediately adjacent the periphery of the doffer. Whereas in the case of many fibers this difference between the two surfaces of the web 2 would not be sufficient to give trouble with breaking down of the ribbons, it appears that certain fibers, such as those having relatively smooth slippery surfaces, or those of a tacky nature, or those of pronounced hydrophobic character, have pronounced differences in their tendency to adhere to adjacent surfaces of tape rolls and the like, depend-

ing upon the fuzzy irregular character of the surfaces of the web itself. Other factors, such as lack of fiber cohesion in the web, may facilitate breaking down of the ribbon once a portion of the fibers therein tend to adhere to the lands 8 rather than the tapes 10. Other factors, which are difficult to evaluate, include static electricity and humidity.

Instead of air pressure being applied, any other fluid medium may be applied, such as an inert gas or dry steam.

It is to be understood that changes and variations may be made without departing from the spirit and scope of the invention as defined in the appended claims.

I claim:

1. In combination, a tape condenser having top and bottom dividing rolls, said rolls having grooves receiving tapes proceeding thereabout, a plain guiding roll associated with each of the dividing rolls for conducting the tapes carrying fiber ribbons away from the dividing rolls, and a conduit extending longitudinally beneath the bottom dividing roll only, means for supplying said conduit with a gaseous fluid under pressure, and a plurality of spaced apertures in said conduit disposed to face the lands of the bottom dividing roll and to direct blasts of fluid against the lands at the exposed portions thereof just in advance of the point of departure of the ribbons as they are carried by the tapes about the lower plain guiding roll.

2. In combination, a tape condenser having

top and bottom dividing rolls, said rolls having grooves receiving tapes proceeding thereabout, a plain guiding roll associated with each of the dividing rolls for conducting the tapes carrying fiber ribbons away from the dividing rolls, and a conduit extending longitudinally beneath the bottom dividing roll only, means for supplying said conduit with a gaseous fluid under pressure, a plurality of spaced apertures in said conduit disposed to face the lands of the bottom dividing roll and to direct blasts of fluid upwardly against the lands at the exposed portions thereof just in advance of the point of departure of the ribbons as they are carried by the tapes about the lower plain guiding roll, nozzles in said apertures, and means for angularly adjusting said conduit.
